INCORPORATED, OF NEW YORK, N. Y., A CORPORATION OF NEW YORK.

SIGNAL-CORRECTING SYSTEM.

1,295,553.

Specification of Letters Patent. Patented Feb. 25, 1919.

Application filed August 14, 1918. Serial No. 249,829.

To all whom it may concern:

Be it known that I, ROBERT C. MATHES, a citizen of the United States, residing at New York, in the county of Bronx and 5 State of New York, have invented certain new and useful Improvements in Signal-Correcting Systems, of which the following is a full, clear, concise, and exact description.

10 This invention relates to telegraphic signaling systems, and more particularly to receiving systems for use in connection with submarine cables or other high-capacity conductors.

15 Its object is to correct for the effect known as wandering zero and thereby to make possible the accurate reception of incoming signals.

It is well known that in signaling over 20 high capacity cables by means of positive and negative impulses, a temporary preponderance of impulses of one polarity will cause a cumulative charging effect in the cable, which manifests itself as an apparent 25 shifting of the zero line in the direction of the impulses, which, for the time being, predominate. The distorted signal wave arriving at the receiving end of the cable may, in other words, be said to consist of two 30 components—one, the high frequency current reversals sent out by the transmitting station, and the other a low frequency variation, representing the fluctuating charge on the cable, following the momentary preponderance of impulses of one or the other 35 polarity.

A somewhat analogous condition may arise in the employment of signal correcting systems such as that described in my co-pending application, No. 240,792, filed June 40 19, 1918.

In such a system where a transformer or 45 an unshunted series condenser is used between the cable and the receiving device the tail of the resultant arrival curve may not be sustained sufficiently to take care of a repeated transmission of impulses of the same polarity, and may fall off to such an extent that such impulses, as for example, 50 a number of succeeding impulses of positive polarity may be represented by actual reversals of current. The point at which such a system fails will depend upon the time constant of the transformer employed, or of 55 the circuit in which the condenser is placed.

While it is possible to build transformers and condenser circuits with sufficiently high time constants to take care of all possible signaling combinations, it may prove preferable to make this correction by employing 60 the local correcting circuit of this invention, wherein the low frequency current representing the variation of the zero line is fed back into the system in such a way as to neutralize itself. This may be effected by 65 the employment of a pair of receiving relays which are electrically biased, the one to respond to positive impulses and the other to respond to negative impulses, and to repeat corresponding signals to a local re- 70 recording device or another signaling conductor. Connected to the output circuit of this relay system is an impedance network or filter whose electrical constants are so chosen as to prevent the passage of impulses 75 of signaling frequencies, but to permit the passage of slower fluctuations such as those represented by the variation in the zero line. This low frequency current is led back into the circuit of the biasing windings of the 80 two relays above mentioned, in such a way as to cause the fluctuating alteration in the biasing current corresponding to the fluctuations of the zero line, but so poled as to its effect on the relays as to neutralize the 85 effect of the fluctuating zeros upon the signals themselves.

The invention will more readily appear from a reference to the accompanying drawing, Figure 1 of which illustrates schematically an arrangement for accomplishing the object of this invention; while Fig. 2 shows one specific form of network which is suitable for use in such a system. In the drawing, 1 represents a telegraphic line conductor connected to ground through the windings 2 and 3, respectively, of two polarized relays 4 and 5. Relays 4 and 5 are provided with biasing windings 6 and 7, supplied with current from the battery 8 to an adjustable resistance 9. The biasing of the relays is such as to maintain their armatures 10 and 11 normally against contacts which are connected to one pole 12 of the battery 13. One of these relays is biased so as to 95 respond to positive impulses, and the other is biased so as to respond to negative impulses, either relay when so responding, moving its armature into contact with the contact stop leading to pole 14 of battery 13, 100 105 110

and thus sending a local current impulse to the circuit of the responsive device 15, in one direction or the other depending upon which relay has been operated. It will, of course, 5 be evident that the responsive device 15 may be any well-known type of telegraphic indicating, recording or retransmitting instrument, and that it may be located either at the cable terminal or at a distant point 10 connected thereto by any telegraph line or cable.

Bridged across the circuit of the responsive device 15 is another circuit containing a correcting network or filter 16, through which 15 a portion of the locally produced signaling impulses is led, by means of the conductors 17 and 18, to the biasing circuit including the windings 6 and 7 of the relays 4 and 5. The network 16 is preferably in the form of 20 that shown in Fig. 2, and is made up of a plurality of shunt elements in the form of condensers 19 and a plurality of series elements in the form of inductances 20 which are preferably shunted by resistances 21. By 25 the selection of proper values for the various capacities, inductances and resistances in the network 16, this network may be made to prevent the passage of high frequency signaling current impulses but to permit the 30 passage of the low frequency component representing the fluctuations of the zero line. Thus, there will be sent through the circuit including the conductors 17, 18 and the two equal resistances 22, a fluctuating current 35 varying in polarity with the momentary preponderance of impulses of one or the other polarity. This will superimpose on the circuit through the biasing windings 6 and 7 a current of correspondingly varying 40 direction, which current will always have the effect of increasing the bias of the one relay and decreasing the bias of the other. By properly poling the superimposed current with reference to the direction of the current 45 supplied by the battery 8, this superimposed current may therefore be made to lessen the sensitiveness of the relay which responds to positive current when the low frequency component has a positive direction, 50 at the same time increasing the sensitiveness of the relay which responds to negative current. Conversely, when the low frequency component is of a negative sign, the sensitiveness of the negative responding 55 relay may be decreased, and that of the positive responding relay increased. It will of course be understood that in the case of the second type of wandering zero above referred to, a different poling of the low frequency current with respect to the main

biasing current will be required for the reason that in this case the zero line has a tendency to move in a direction opposite to that of the predominating impulse polarity. In either case, however, the effect of the low 65 frequency current in the biasing circuit is opposed to the direct effect on the signals themselves. The amount of the low frequency current which is fed back into the biasing circuit may be adjusted at will by 70 means of a variable resistance 23, bridged across the circuit of the conductors 17 and 18, as shown. It is thus seen an arrangement is provided whereby, as soon as there is a tendency for the zero line to shift, either 75 positively or negatively, there is produced counteracting and automatic adjustment of the sensitiveness of the two relays, so that their response may be made practically independent of the fluctuating zero, and the 80 signals transmitted to the responsive device 15 will thus be practically undistorted.

The specific arrangement shown for connecting the battery 8 and the conductors 17 and 18 of the low frequency circuit to the 85 biasing circuit is not essential. The direct current source and the low frequency source can in fact be interchanged without interfering with the operativeness of the system, the main requirement being that the direct 90 current biasing source and the low frequency source should be the mutually conjugate circuits.

What is claimed is:

1. In a telegraph receiving system, a line 95 conductor, a pair of biased relays in circuit with said conductor and selectively responsive to signaling currents therein, and means for changing the bias of said relays according to fluctuations in the apparent zero line 100 of said signal currents.

2. In a signaling system, a transmission line, a pair of relays in circuit with said line and responding to positive and negative impulses respectively, a responsive device and circuit therefor, contacts in said circuit controlled by said relays for actuating said device, auxiliary windings and circuit connections for biasing said relays in opposite directions, a branch circuit extending from the 110 circuit of said responsive device to said biasing circuit, and means in said branch circuit for preventing the passage therethrough of impulses of signaling frequencies while permitting the passage of relatively low frequency current variations.

In witness whereof, I hereunto subscribe my name this 5th day of August A. D., 1918.

ROBERT C. MATHES.
